UNITED STATES PATENT OFFICE.

JULIUS C. DICKEY, OF SARATOGA SPRINGS, NEW YORK.

HARNESS-SADDLETREE.

Specification of Letters Patent No. 12,481, dated March 6, 1855.

To all whom it may concern:

Be it known that I, JULIUS C. DICKEY, of Saratoga Springs, in the county of Saratoga, and State of New York, have invented 5 a certain new and Improved Mode of Constructing Pad-Trees for Harness; and I do hereby declare that the following is a full and exact description thereof, reference being had to the accompanying drawings, 10 forming a part of this specification.

The nature of my invention consists in an elongation of the nut which is secured in the adjustable jockey plate by which elongation the turrets may be secured to the yoke in 15 any desirable position, and also secure the adjustable jockey plates to the yoke, in combination with the said nut and a projection which is cast on the under side of the yoke which is inserted in a hole in the said nut.

20 Figure 1 represents a view in perspective of my improved pad tree, with one skirt removed in order to show the clamp plate. Fig. 2 is a vertical longitudinal section of one side of the tree. Fig. 3, is a cross section of the same through the line α α of Fig. 2.

In Fig. 1 letter A, is the yoke; B, the turrets; C, the check hook; D, the adjustable jockey plates; E, the clamp plate; F, the 30 skirts.

In Fig. 2, A, shows the jockey shaped side bar or yoke. C, C, C, the plate which secures the adjustable jockey plate to the side bars or yoke in connection with the turret, 35 and the projection on the under side of the side bars; α α , and dotted lines shows the projection on the under side of the side bars; D the adjustable jockey plate, and f, the plate, which secures the plate in the adjustable jockey plate, which secures the adjustable jockey plate to the side bars or yoke.

In Fig. 3, A shows the side bars; e the

projection on the under side of the same; C C the intermediate plate; D the adjustable jockey plate, and f the plate which secures the intermediate plate in the adjustable jockey plate.

The yoke A, in Fig. 1, is formed into a properly shaped harness saddle seat, with 50 the jockey shaped side bars, and a projection is cast on the under side of the side bars which is inserted into a hole in plate C, as shown in Fig. 2, and Fig. 3. The side bars are perforated to receive the turrets 55 B, B, which screw into the plate C, as shown in Fig. 2, and Fig. 3, plate C being secured to the adjustable jockey plate, which secures the adjustable jockey plate to the side bars or yoke.

The plate or nut C, C, C, as shown in Fig. 2, and Fig. 3, I elongate, by which elongation, the turrets B B, may be secured to the yoke A, in any desirable position, and also secure the adjustable jockey plates D D, 60 to the yoke A, in combination with the plate or nut C C C, and the projection cast on the underside of the yoke A, which is inserted in a hole in plate or nut C, C, C.

The skirt F, I secure to the adjustable 70 jockey plate as patented by me August 29th, 1854.

I claim—

The shank piece or prolongation of the nut C, for the purpose of enabling me to 75 place the turrets higher up on the yoke, where they properly belong, and to prevent the reins, passing through them, from being too much spread at that point, as they would be if the turrets were placed at the joint 80 which is limited in its position, substantially as set forth.

JULIUS C. DICKEY.
